UNITED STATES PATENT OFFICE.

GLENN H. CURTISS, OF BUFFALO, NEW YORK, ASSIGNOR TO CURTISS AEROPLANE AND MOTOR CORPORATION, A CORPORATION OF NEW YORK.

BOAT-TYPE WING-PONTOON.

1,246,017.

Specification of Letters Patent.

Patented Nov. 6, 1917.

Application filed August 12, 1916. Serial No. 114,532.

To all whom it may concern:

Be it known that I, GLENN H. CURTISS, a citizen of the United States, residing at Buffalo, in the county of Erie and State of New York, have invented certain new and useful Improvements in Boat-Type Wing-Pontoons, of which the following is a specification.

My invention relates to aircraft equipment and has reference more particularly to wing pontoons for hydroaeroplanes or flying boats.

Ordinarily wing pontoons are constructed to present a flat hydroplaning bottom having an angle of incidence considerably greater than the angle of incidence of the wings. In all pontoons it is essential that the connection with the aeroplane wing be absolutely rigid; that the bottom of the pontoon possess hydroplaning characteristics; and that the pontoon be constructed in substantially streamline form. Heretofore the pontoons have been dropped down quite some distance below the wings and effectually trussed to one or more of the wing beams, the resultant center of hydroplane lift lying considerably aft of the vertical plane of the center of air lift.

The above construction, although serviceable, is incapable of withstanding effectually the heavy strains incurred by use in rough water and in connection with flying boats and hydroaeroplanes of large size. Many disadvantages, structurally, are found to exist. By the present invention it is proposed to locate the resultant center of hydroplane lift in the approximate vertical plane of the center of air lift. The hydroplaning surface of the pontoon is therefore brought forward. To do this, without structurally changing the type of pontoon now extant, would require that the forward end of the pontoon extend considerably in advance of the leading edge of the wings and that the supporting struts extend rearwardly for anchorage preferably in the plane of the wing beams. Obviously, this arrangement would be impractical and conducive to greatly increased head resistance incident to flight. Moreover, the larger the pontoon the greater the strains. Particularly is this true in rough water. Hence, to meet these conditions which arise through increased bulk and yet maintain the center of hydroplane lift at the point desired, it is

proposed by this invention to construct the pontoon along radically different lines, *i.e.*— lines which provide for the elimination of the flexible paddle often used and the marked angle of incidence heretofore required.

By the present invention is it proposed therefore; first, to increase the buoyancy or sustaining capacity of the wing pontoon; second, to increase materially its hydroplaning area; third, to increase considerably its seaworthiness and strength; fourth, to locate the center of hydroplane lift in the approximate vertical plane of the center of pressure and accordingly eliminate the bending moment ordinarily found where the center of hydroplane lift is located aft of the rear wing spar beneath which the pontoon is arranged; fifth, to produce an increased area adapted for anti-skid purposes; and finally, to increase respectively the buoyancy, hydroplane area, seaworthiness, rigidity and anti-skid area without increasing in any way the head resistance. These advantages I attain in the particular manner and by the particular construction hereinafter pointed out.

In its broad aspect, each wing pontoon may be said to partake of the general characteristics and attitude of a boat. The hydroplaning surface is made an integral part of the pontoon body or hull and constructed to split or cut the water in traveling at speed over the surface thereof. From the bow end of the hull, the bottom, at the chines, extends downwardly and rearwardly to a point well aft where it is slightly upwardly inclined or curved. The curvature of the keel is different. From a point where the keel and stem join, the keel extends abruptly downwardly and slightly rearwardly and then more horizontally rearwardly and slightly downwardly to a point approximately amidships where it continues aft on an upwardly and rearwardly inclined curve, terminating at its extreme after end at a point where the chine-stringers and stern post meet. This difference in curvature between the chines and the keel will give to the hull bottom a convex form both longitudinally and transversely, the convexity (transversely) decreasing gradually from a point well forward to flatness at the stern. The sides of the hull are bowed in streamline form fore and aft and extend at right

100

105

110

angles to the deck which is horizontally flat or nearly so. Interiorly, the hull is braced and trussed to secure rigidity and strength.

In the drawings, wherein like characters 5 of reference designate like or corresponding parts throughout the several views:

Figure 1 is a longitudinal vertical sectional view of a wing pontoon having the characteristics of a boat and constructed in 10 accordance herewith;

Fig. 2 is a horizontal longitudinal sectional view (one half of the hull having been removed);

Fig. 3 is a transverse section on the line 15 3—3 of Fig. 2;

Fig. 4 is a similar view on the line 4—4 of Fig. 2;

Fig. 5 is a similar view on the line 5—5 of Fig. 2;

Fig. 6 is a fragmentary top plan view 20 illustrating the manner in which the pontoon is fastened to its supporting wing;

Fig. 7 is a front elevation of a hydro-aeroplane equipped with boat type pontoons 25 to accordingly illustrate the similarity between the hydroplaning bottom of each pontoon and the main or center flotation body of the craft;

Fig. 8 is a view similar to Fig. 1 illustrating a modification;

Fig. 9 is a top plan view of the modified pontoon illustrated in Fig. 8;

Fig. 10 is a transverse section on the line 10—10 of Fig. 8.

Fig. 11 is a transverse section on the line 35 11—11 of Fig. 8, and

Figs. 12, 13 and 14 illustrate details of the modification.

The pontoon structure which I consider 40 preferred I have illustrated in Figs. 1—7 inclusive. With reference particularly to Fig. 7 wherein I have illustrated diagrammatically a hydroaeroplane equipped with wing pontoons of the present invention, the numeral 15 designates the main or center flotation body, 16 the end flotation bodies or wing pontoons (each designated in its entirety), and 17 the aeroplanes or supporting surfaces, of which, in the diagram illustrated there are two. The main or center flotation body 15 is of the well known Curtiss type which, when viewed in elevation (front) presents a hydroplaning surface of V-form in transverse section, the angle of 45 the V decreasing to flatness at a point approximately amidships where the usual rearwardly facing step (not shown) is formed. Excrecent structures or bilge fins continue the hydroplaning bottom of the 50 main flotation surface laterally beyond the chines to increase the boat displacement. The foregoing and other well known features of the Curtiss machine characterize the hull.

60 The wing pontoons 16 are much smaller

and like the wing pontoons of all hydro-aeromachines arranged beneath the lower supporting surface, one at each side of the longitudinal axis of the craft, preferably at the very tip of each wing. In form and attitude, the pontoons 16 are somewhat similar to the main flotation body 15 in that each has the characteristics and water engaging position of a boat and in size is capable of sustaining not only the weight 75 of the aeroplane wing beneath which it is arranged but each the additional weight of an adult in case of an emergency.

In construction, the wing pontoons are alike. Each pontoon at its forward end is 80 shaped to streamline form and equipped with a vertically pointed prow. The underneath surface of the pontoon or hull is generally flat and shaped both transversely and longitudinally to present to the water 85 a hydroplaning surface of approved and accepted form. The hull sides throughout extend vertically and merge both fore and aft respectively into the stem and stern post later to be described. This construction 90 will give to the pontoon a perfect streamline form and at the same time present a hydroplaning surface of increased area and one which is capable of entering and splitting the water in traveling at speed thereon. The transverse section of the hydroplaning bottom, by the action of water thereon, cushions the impact of the water while hydroplaning and at the same time decreases the water resistance to forward 95 travel at speed. The deck of the pontoon is substantially horizontally flat.

In constructing the pontoon, the keel 18 is first laid and the remaining structural elements assembled symmetrically with respect thereto. The keel at its forward end extends vertically, the vertical prolongation constituting the stem of the hull which I have herein designated 19. From the stem aft, the keel is curved rearwardly and downwardly to a point 20 where the curvature continues more horizontally to a point 21 approximately amidships. At this point the curvature swings gradually upwardly until an abrupt terminus is reached at the stern. The stern post to which the keel is fastened at its extreme after end is designated 22. The stem 19 and the stern post 22 extend vertically and substantially parallel.

Chine stringers 23, symmetrically and oppositely curved or bowed both horizontally and vertically, interconnect the stem 19 and the stern post 22. The curvature of the chine stringers 23 although somewhat similar to the curvature of the keel 18 is less marked and more regular, having a gradually downward and rearward curvature from stem to stern. This difference in curvature between the chine stringers and the keel will give to the hydroplaning bottom 120

125

130

the desired or required form. At the extreme forward end of the pontoon the hydroplaning bottom is characterized by convexity of V-form, the angle of the V at this point being relatively small. From the forward end aft the angle increases gradually, accordingly decreasing the convexity to flatness at the stern. Fig. 1 considered in connection with the transverse sections, Figs. 10 3, 4 and 5, illustrate clearly the shape and character of the hydroplaning surface both fore and aft. The hydroplaning bottom, when viewed in section, and at each side of the keel is symmetrically and very slightly 15 concave, this curvature, while hydroplaning, directing the displaced water laterally and downwardly that the cushioning feature may result.

Interiorly, the hull or pontoon is braced 20 and trussed both transversely and longitudinally after a fashion illustrated in Figs. 1 and 2. Deck stringers 24 which extend parallel with the chine stringers 23, and side stringers 25, constitute with the stem 25 19, the stern post 22, the keel 18, a false keel 26, an upper breast hook 27, a lower breast hook 28, an upper tail plate 29, and a lower tail plate 30, a frame to which the planking, flooring, beams and struts are fastened. 30 Deck beams 31 interconnect the deck stringers 24, longitudinally brace the stringers, and at the same time afford a base or bed for the deck planking 32. Side struts or frames 33 interconnect the deck stringers and the 35 chine stringers and like the deck beams 31 afford a bed (not for the deck planking) but for the side planking 34. The flooring or bottom planking 35 is fastened to the bent floor beams 36 which interconnect the 40 chine stringers and engage equidistant from their ends with the keel. Bulkheads 37 divide the pontoon or hull transversely into watertight compartments although the forward bulkhead, designated 38, is non-watertight as shown.

To brace the hull from stem to stern, cross braces 39 and crossed diagonals 40 are located 50 interiorly thereof. The aftermost crossed diagonals engage respectively with the flooring at the chine stringers and with the deck at the deck stringers. The intermediate crossed diagonals are similarly arranged though oppositely inclined. They form with the rear crossed diagonals an inverted V-brace in side elevation. In other words, both sets of diagonals engage with the chine stringers in such manner that they 55 form the apex of the inverted V-brace. Battens 41 and V-arranged braces 42 also 60 interiorly and strongly brace the hull. The cross braces 39 are preferably located substantially amidships or at a point in the approximate vertical plane of that point designated 21 where the keel 18 begins to assume 65 an upwardly and rearwardly inclined curve.

While any appropriate fastening means may be used it is preferred that the pontoons lie close up under the aeroplane wings for securement directly to the wing spars herein designated 43. Bolts 44 engage with the wing spars at opposite sides thereof (so as not to weaken them) and with the pontoon beneath the deck planking 32. A plate 45 is arranged over the bolt terminals extended above the wing spar to constitute 70 with nuts 46 a fastening means. The arrangement of the pontoon with respect to the wing spars is best illustrated in Fig. 1.

By constructing the wing pontoons in the manner described and fastening each 80 wing pontoon close up under the wing with the sides of the pontoon extending vertically, or nearly so, a flotation body of considerable displacement and buoyancy is produced. A pointed prow will permit the hydroplaning surface to be brought considerably forward and in fact forward to a point in the approximate vertical plane of the entering edge of the wing. This construction not only increases the hydroplaning area 90 but eliminates the wing bending moment ordinarily found where the center of hydroplane lift is located aft of the rear wing spar beneath which the pontoon is arranged. The depth of applicant's pontoon is approximately the same both fore and aft with 95 its greatest depth substantially amidships. The depth at the prow in fact is quite substantial and the same may be said to extend downwardly substantially vertically from 100 the wing near to the water surface. Seaworthiness of the pontoon is thus increased and the anti-skid surface actually enlarged whereby greater stability in flight will result. The head resistance is in no way increased. Briefly, the pontoon may be said to partake of the characteristics of a boat in structure, position, function and design, yet as compared with the center float the pontoon sustains no substantial portion of the 110 total load.

With reference to the modification illustrated in Figs. 8-14 inclusive, it will be noted that this pontoon is differently constructed. In the modification, the stem 19' 115 extends horizontally rather than vertically and the keel 18', false keel 26' and chine stringers 23' extend aft therefrom on a downward and rearward curve and substantially in parallelism throughout the 120 greater portion of their length. The prow end of the pontoon is thus broad and flat. At the rear, the chine stringers 23' merge and engage at a point where the stern post 22' and keel 18' are joined. Although having a convex hydroplaning bottom from 125 stem to stern, the convexity, unlike that disclosed with reference to the preferred type of pontoon, is shallow and laterally of the keel perfectly flat. The convexity of the 130

hydroplane bottom merges gradually into flatness both fore and aft. In other respects, the pontoon is quite similar to that which I have designated as preferred. Deck 5 stringers 24' interconnect the stem and stern post and with deck beams 31' constitute a bed for the deck 32'. Side frames or beams 33' extend from the deck stringers 24' to the chine stringers 28' vertically and 10 in parallelism to afford a support for the side planking 34'. Bent floor beams 36' join the chine stringers and engage with the keel. Other structural details such as the water tight bulkhead 37', the cross bracing 15 39' and bottom planking 35' will be understood by reference to Figs. 8 and 11. If desired, drain plugs 50' may be provided.

In both instances, the pontoon structure is of a streamline form and equipped with 20 ample hydroplaning surface to insure the desired hydroplaning action in use. The integrally formed V-bottom disclosed is particularly desirable in that each pontoon may thus partake of the characteristics of a 25 boat and afford, in emergency, a means whereby the aviator or other person if thrown into the water may regain control of his machine by climbing onto the wing pontoon and after gaining a footing proceed via the wing to the main flotation body. It is for this reason as well as the increased 30 hydroplaning area produced that the wing pontoons are constructed in size large enough to sustain in addition to the weight 35 of the aeroplanes, an adult person.

While in the foregoing I have illustrated and described wing pontoons of a more or less specific construction, it is to be understood that I do not intend to limit myself except in so far as the claims demand.

In conclusion, it is to be noted that the sides of the hull structure extend perpendicularly to the aeroplane surface; that the depths of the pontoon are approximately 45 equal both fore and aft and that I have produced an integrally formed hydroplaning bottom transversely convex from the bow rearwardly.

What is claimed is:

50 1. In a hydro-aero-machine, the combination with aeroplane wings, of wing pontoons having the characteristics and attitude of a boat, each pontoon having a hydroplane bottom such that its resultant center of hydroplane lift lies substantially below the center of lift of said wings.

2. In a hydro-aero-machine, the combination with aeroplane wings, of a main flotation body having the characteristics and 60 attitude of a boat, and wing pontoons similarly characterized, each pontoon having a hydroplane bottom of substantially V-form in transverse section at its forward end, said forward end being distantly removed

from the plane of the wing beneath which it 65 is disposed.

3. In a hydro-aero-machine, the combination with aeroplane wings, of a main flotation body having the characteristics and attitude of a boat, the wing pontoons having a 70 cut-water bow and a transversely convexed bottom, said bottom being in hydroplaning form and so located with respect to said aeroplane wings that its resultant center of hydroplane lift lies substantially beneath the 75 center of lift.

4. In a hydro-aero-machine, the combination with aeroplane wings, of wing pontoons including a hydroplaning bottom disposed substantially uniformly distant from 80 said wing, and forwardly converging substantially vertical sides built up from said bottom to provide at the forward end of the pontoon a cut water bow.

5. In a hydro-aero-machine, the combination with aeroplane wings, of wing pontoons including a hydroplaning bottom disposed substantially uniformly distant from 90 said aeroplane wings, trussing for said bottom, and sides built up from said bottom to said wings, said sides inclosing said trussing and giving to the pontoon the characteristics and attitude of a boat.

6. In a hydro-aero-machine, the combination with aeroplane wings, of wing pontoons having a transversely convexed hydroplaning bottom and a cut-water bow, said bottom underlying said aeroplane wings and terminating forwardly at a point in the approximate vertical plane of the leading edge 100 of said wings and at a point distantly removed therefrom.

7. In a hydro-aero-machine, the combination with aeroplane wings, wing pontoons including a hydroplane bottom surface having its forward portion characterized by transverse convexity, and sides built up from said bottom in such manner that at the said forward end the pontoon is given a streamline entry and a cut-water bow. 105

8. In a hydro-aero-machine, the combination with aeroplane wings, of wing pontoons including a hydroplaning bottom disposed substantially uniformly distant from 115 said aeroplane wing throughout its length, said bottom being characterized by transverse convexity, the convexity decreasing gradually from stem to stern, and sides built up from said bottom to form therewith a pontoon of substantially boat form.

9. In a hydro-aero-machine, the combination with aeroplane wings, of wing pontoons including a hydroplaning bottom disposed substantially uniformly distant from 125 said wings throughout its length, said bottom being characterized by longitudinal and transverse saliency, the saliency in the transverse plane increasing gradually to-

ward the stern, and forwardly converging substantially vertical sides built up from said bottom to form therewith a pontoon having the characteristics and attitude of 5 a boat, the forward convergence of the sides giving to the pontoon a cut-water bow.

10. In a hydro-aero-machine, the combination with aeroplane wings, of wing pontoons arranged beneath said wings, each 10 pontoon comprising a hydroplane bottom disposed vertically distant from said wings throughout its length, said bottom commencing at a point in the approximate vertical plane of the leading edge of said wings 15 whereby the resultant center of hydroplane lift lies approximately below the center of lift, and sides built up from said bottom to said wings, said sides forming with said bottom a pontoon having the characteristics 20 and attitude of a boat.

11. In a hydro-aero-machine, the combination with aeroplane wings, of wing pontoons having a forward depth approxi-

mately equal to the depth aft, a hydroplaning bottom, and substantially vertical sides 25 built up from said bottom, said sides converging upwardly to provide in effect a cut-water bow.

12. In a hydro-aero-machine, the combination with aeroplane wings, of wing pontoons comprising a hydroplaning bottom disposed vertically distant from said wings such that the depth of the pontoon may be approximately equal from stem to stern, said bottom in transverse section being 30 characterized by saliency, the saliency increasing toward the stern, means directly trussing said bottom to the aeroplane wings, and sides built up from said bottom to said wings to inclose said trussing, said sides 35 converging both fore and aft for stream-line purposes and for the purpose of giving to the pontoon a cut-water bow.

In testimony whereof I affix my signature.

GLENN H. CURTISS.
